UNITED STATES PATENT OFFICE.

RUDOLPH VUILLEUMIER, OF NEW ROCHELLE, NEW YORK, ASSIGNOR TO THE SAFETY CAR HEATING & LIGHTING COMPANY, A CORPORATION OF NEW JERSEY.

APPARATUS FOR APPLYING HEAT AND METHOD OF USING SUCH APPARATUS.

Application filed May 5, 1917. Serial No. 166,878.

To all whom it may concern:

Be it known that I, RUDOLPH VUILLEUMIER, a citizen of the United States, and a resident of New Rochelle, in the county of 5 Westchester and State of New York, have invented an Improvement in Apparatus for Applying Heat and Methods of Using Such Apparatus, of which the following is a specification.

10 This invention relates to means and processes for providing a heated surface, and with regard to its more specific features, to an apparatus for making gas and a method of using the same. One of the objects there- 15 of is to provide practical and efficient apparatus adapted to offer a highly heated surface. Another object is to provide apparatus of the above nature characterized by uniformity and economy in action. Another 20 object is to provide an improved method or art whereby a highly and uniformly heated surface is developed. Other objects will be in part obvious and in part pointed out hereinafter.

25 The invention accordingly consists in the features of construction, combinations of elements, arrangements of parts, and in the several steps and relation of such steps as will be hereinafter illustratively described 30 and the scope of the application of which will be indicated in the following claims.

In the accompanying drawing, in which is shown one of various possible embodiments of the mechanical features of this invention.

35 Figure 1 is a sectional elevation of the same;

Figure 2 is a sectional bottom plan taken along the line 2—2 of Figure 1; and

40 Figure 3 is a sectional plan taken along the line 3—3 of Figure 1.

Similar reference characters refer to similar parts throughout the several views of the drawing.

45 Referring now to Figure 1 of the drawing, there is shown a gas generator comprising the outer steel shell 10 lined with fire brick or other suitable substance to provide the wall 11. At the base of this apparatus, there is formed a combustion chamber 12, the arch or roof of which, also formed of fire brick, converges upwardly toward the outlet port 13. Positioned immediately above the passage 13 is a deflecting plate 14 preferably circular in form and 50 resting on the radial arms 15, best shown

in Figure 2 of the drawing. These arms taper at their innermost ends and provide radial passages through which the gases can escape upwardly to the checker-work indicated at 16. This checker-work is of the usual form and requires no detailed description. At the upper end of the checker-work is a chamber 17 which leads to the stack or up-take 18 controlled by a suitable swinging gate 19.

55 Leading into the combustion chamber 12 in a tangential direction, as indicated in Figure 3, is the inlet passage 20 through which air for combustion is either drawn or forced. This passage is controlled as by the gate-valve 21 and provided with the central fuel supply tube 22 through which the liquid fuel, as for example, tar, is blown as by steam. This incoming jet of flame or burning gases is thrown powerfully in a tangential direction into the combustion chamber, and results in a whirl or vortex which draws inwardly toward the center of the chamber at a greatly increased angular speed due to the principle of the conservation of linear momentum. The whirling gases then pass upwardly through the passage 13, and striking the deflector 14, are thrown outwardly and thence ascend in a substantially uniform volume through the checker-work. This uniformity of distribution is insured by the outward throw of the gases as they encounter the radial supporting arms 15 although a high degree of uniformity may be achieved merely from the vortex or whirling action even if the support for the plate be of another type.

60 By this action, the checker-work is exposed to a heat which is uniform in a horizontal plane, that is, the radially outermost portion is just as highly heated as that immediately above the center of the combustion chamber, and the distribution in angular direction is likewise uniform.

The gases being thus to some extent cooled, they pass off through the stack 18.

65 In order to render more uniform the heating of the upper and lower portions of the checker-work without sacrificing economy of action of the apparatus, there is provided a by-pass 23 from the chamber 17 which curves downwardly through the gate-valve 24 and thence, the gate 25 being closed, inwardly through a passage 26 to the passage or port 13. In this manner, the gases from

chamber 17 which are materially cooled, are mixed with the extremely hot gases arising from the combustion chamber, and thus the temperature of the latter materially reduced. It is to be understood that if the apparatus is started cold, it is first heated to a considerable extent before this by-pass is opened, and it is also to be understood that the circulation through the by-pass is 10 rendered more positive as by a jet of steam from the pipe 27 blown downwardly as indicated. There is thus no excessive air provided and the combustion is fully as economical as though the by-pass were not used; 15 yet the uniformity of heating of the checker-work in a vertical direction is greatly enhanced.

It may be noted that the arrows shown in full lines in the drawing indicate the course 20 of the gases when the apparatus is being utilized to heat the checker-work, and that the dotted arrows indicate the course of the gases during the manufacture of gas as hereinafter described.

25 When the checker-work has reached the desired intensity of heat, the gate-valves 21 and 24 and the cover gate-valve 19 are closed, and the gate-valve 25 opened. With the parts in this position, a suitable oil is 30 blown into the chamber 17 as by means of the atomizing nozzles 28. This oil striking the checker-work is cracked or converted into gas and passes downwardly through the port 13 and passage 26 and is drawn off 35 through the gate-valve 25. When the checker-work has cooled to such an extent that the cracking of the vapors is inefficient, the supply of oil is cut off from the nozzles 28, and by reversing the position of the 40 above gate-valves and turning on the fuel jet, the checker-work is again heated as above described.

It will thus be seen that there is provided 45 apparatus and an art in which the several objects of this invention are achieved and that in this apparatus the action is essentially practical and efficient and the results in the matter of uniformity and effectiveness are economically gained. Also it may be 50 noted that many of the features of this invention are of value in other relations, although peculiarly advantageous in a relation such as that herein described.

As various possible changes might be made 55 in the above apparatus and as the above-described art might be carried on by the use of different devices, it is to be understood that all matter herein described or shown in the accompanying drawing is to be interpreted as illustrative and not in a limiting 60 sense.

I claim as my invention:

1. In apparatus of the class described, in combination, means provided with a heat- 65 absorbing surface, means forming a com-

bustion chamber, means adapted to admit fuel and air to said combustion chamber in proportion for substantially full combustion of said fuel, means adapted to lead the products of combustion over said heat-absorbing surface, and means adapted to return a portion of said products of combustion to a point immediately preceding the passage over said heat-absorbing surface in sufficient volume materially to reduce the 75 temperature of products of later combustion entering said first means.

2. In apparatus of the class described, in combination, a combustion chamber, checker-work mounted above said combustion chamber, means forming a passage leading from said combustion chamber to the lower side of said checker-work, means forming a chamber above said checker-work and provided with an outlet, and means independent of said outlet adapted to lead gases from said second chamber downwardly into said gases from said combustion chamber beneath said checker-work and thereby reduce the temperature 85 of gases entering said checkerwork. 90

3. In apparatus of the class described, in combination, an upright container provided with a combustion chamber at its lower part and an outlet at its upper part, checker-work mounted in the body of said container, means forming a lateral passage leading into said container intermediate said checker-work and said combustion chamber, a by-pass leading from said upper chamber downwardly into said passage, and means controlling the passage through said by-pass. 100

4. In apparatus of the class described, in combination, an upright container provided with a combustion chamber at its lower part and an outlet at its upper part, checker-work mounted in the body of said container, means forming a lateral passage leading into said container intermediate said checker-work and said combustion chamber, a by-pass leading from said upper chamber downwardly into said passage, means controlling the passage through said by-pass, means adapted to discharge a gas-producing fluid into said upper chamber, means adapted to withdraw and lead off gas through said intermediate passage, and a valve controlling said last means. 110 115

5. In apparatus of the class described, in combination, checker-work, means forming a combustion chamber beneath said checker-work, means forming a central passage leading upwardly from said combustion chamber to said checker-work, means adapted to force fluid tangentially into said combustion chamber, a baffle plate mounted above said central passage and below said checkerwork, and radially extending arms supporting said baffle plate. 120 125

6. In apparatus of the class described, in combination, means provided with a heat- 130

- absorbing surface, means forming a combustion chamber, means adapted to lead gases from said combustion chamber through said heat-absorbing means, means adapted to lead 5 gases from the remote side of said heat-absorbing means back into said gases on the inlet side of said heat-absorbing means, and means adapted to cause rotation of the burning gases in said combustion chamber.
- 10 7. In apparatus of the class described, in combination, an upright container provided with a combustion chamber at its lower part and an outlet at its upper part, checkerwork mounted in the body of said container with 15 an upper chamber formed above the same, means forming a lateral passage leading into said container intermediate said checkerwork and said combustion chamber, a by-pass leading from said upper chamber downwardly into said passage, means controlling the passage through said by-pass, and means adapted to force a fluid tangentially into said combustion chamber.
- 10 8. The art of heating checkerwork which
- consists in leading gases upwardly through 25 the checkerwork, withdrawing a portion of said gases from the upper side of said checkerwork after said checkerwork has been partially heated, and leading the gases so withdrawn into those at the lower side 30 of said checkerwork and thereby reducing the temperature of the gases entering said checkerwork.
9. The art which consists in producing combustion with substantially full air supply, leading the products of combustion through a body to be heated, withdrawing a substantial portion of said products subsequent to passage through said body, and leading the same into intermingling relation with products of later combustion immediately prior to their passage through 35 said body.
- In testimony whereof, I have signed my name to this specification this 1st day of 40 May, 1917.

RUDOLPH VUILLEUMIER.
